(57) CLAIM

The ornamental design for a protective lid cover for a removable lid, as shown and described.

DESCRIPTION

FIG. 1 is a top perspective view of the protective lid cover for a removable lid.

FIG. 2 is a bottom perspective view of the protective lid cover for a removable lid.

FIG. 3 is a top perspective view of the protective lid cover for a removable lid in use.

FIG. 4 is a bottom perspective view of the protective lid cover for a removable lid in use.

FIG. 5 is a top plan view of the protective lid cover for a removable lid.

FIG. 6 is a bottom plan view of the protective lid cover for a removable lid.

FIG. 7 is a front view of the protective lid cover for a removable lid; and,

FIG. 8 is a left side view of the protective lid cover for a removable lid.

The broken lines in FIGS. 3 and 4 depict a cup with a removable lid showing the environment forming no part of the claimed design.
